UNITED STATES PATENT OFFICE

2,470,962

FIGURINE BALL PROJECTOR

Harvey M. Wescott, South Westport, Mass.

Application September 26, 1946, Serial No. 699,403

1 Claim. (Cl. 124—7)

1

This invention relates to the class of articles provided for amusement and more particularly to games wherein a certain amount of skill is required of the player in order to aim a projected ball so as to enter a target receptacle and thereby be scored in the player's favor. A novel and amusing game is provided in which a miniature figure of a bowler is controlled by the player and simulates bowling a ball in a lifelike manner toward certain receptacles for the purpose of scoring.

Another object of the invention is the provision of a novel and amusing game which is simple in construction and operation and also inexpensive in cost of manufacture.

The above and other objects will become apparent in the following description wherein characters of reference refer to like-numbered parts in the accompanying drawing. It is to be noted that the drawing is intended for the purpose of illustration only and that it is neither desired nor intended to limit the invention to any or all of the specific details of construction shown excepting insofar as they may be deemed essential to the invention.

Referring briefly to the drawing, Fig. 1 is a plan view of the game board.

Fig. 2 is a view taken on the line 2—2 of Fig. 1.

Fig. 3 is a sectional view taken on the line 3—3 of Fig. 1.

Fig. 4 is a sectional view taken on the line 4—4 of Fig. 1.

Fig. 5 is a sectional view taken on the line 5—5 of Fig. 2.

Fig. 6 is a sectional view taken on the line 6—6 of Fig. 1.

Referring in detail to the drawing, the numeral 10 indicates the base board of the game apparatus, which is rectangular in shape and substantially greater in length than in width, thus simulating a bowling alley to some degree. Rigid thereto and depending from the margins of the base board 10 are a pair of side walls 12, a front wall 11, and a rear wall 13, all of which serve to elevate the base 10 above the surface on which the game board is resting during use, thus allowing clearance for the concealed mechanical features beneath the base. A plurality of ramps 14, each having its lower end toward the front, and flush with the surface, of the board 10 and provided with a cup 15 at its upper end, is provided at the rear of the board 10, being rigidly attached thereto as by means of screws 16 and positioned in a manner that the axis of each ramp if extended would pass approximately through a

2

point in the center of the front edge of the board 10.

A raised wall 17 of substantially the shape shown surrounds the rear half of the board 10. A transverse slot 20 is cut in the base 10 near its front end in substantially the location shown. A miniature figure of a bowler 18 having a spring-operated right arm 19 is rigidly mounted on a frame 21, the latter having guide pins 22 rigid thereto and registering in the slot 20 and thus being slidably mounted on the base board 10.

The actuating mechanism of the bowler's arm comprises a pivot pin 23, a lever 24 keyed thereto and having one end secured to a spring 25 and the other end secured to a cord or flexible wire 26 which passes downward through a hole 27 in the base of the figure 18, through the slot 20, thence through a slot 28 in the front wall 11, through a hole 29 of the vertical member 30 depending from the frame 21, and is secured to a knob 28a normally positioned against the member 30 by urging of the spring 25 on the linkage described. The anchored end of the spring is fixed to a transverse pin 32 rigidly secured inside the figure 18 and positioned parallel to the pivot pin 23 and within the arc of the lever 24, thus providing a limit stop to the motion of the lever, when the latter is urged in a counter-clockwise direction by the spring 25.

The right arm 19 of the bowler 18 is rigidly secured to the end of the pivot pin 23 and so positioned that when the lever 24 rests against the pin 32 at its limit of travel the arm 19 is in substantially vertical position. The hand 31 of the arm 19 is gouged out in cup-like fashion and thus adapted to hold a ball or marble 34. Spare balls 34 are provided near the bowler in a rack 35 where they may be readily reached by the player, and at the same time enhance the illusion of the miniature bowler and alley.

To play the game, the operator places a ball 34 in the hand of the miniature figure, then aligns the same with a desired ramp by sliding the frame 21, by grasping the rigid handle extensions 45 30a of the member 30, in the slot until the desired position is located. When the bowler is positioned as desired, the knob 28a is pulled out, thereby pulling the cord 26 and rotating the lever 24 in a clockwise direction against the force of the spring 25. The knob 28a is then suddenly released, allowing the energy of the spring to rotate the lever forcibly counter-clockwise until it hits the limit stop 32, thus impelling the ball from the hand and up the alley and preferably up one of the ramps 14 to lodge in one of the

cups 15. The cups 15 may be marked with varying numbers of points scored and the total number of points for a given number of throws by a player would then be his score for the game. Obviously, any number of players could participate, each taking his turn and taking an arbitrary number of throws as decided upon by the players.

Obviously, modifications in form and structure may be made without departing from the spirit and scope of the invention.

I claim:

A game apparatus comprising a board, a figure mounted on said board adjacent one end thereof and facing the other end thereof, said figure having an arm depending therefrom and pivoted thereto, said arm having a cup-shaped ball receptacle at the lower end thereof adapted to receive a ball, means for swinging said arm in a rearward direction through an arc, resilient means normally urging said arm in a forward direction, a limit stop to the forward swinging of said arm, said first-named means being releasable and upon release thereof after swinging said arm through said arc in the rearward direction permitting said resilient means to swing said arm suddenly through said arc thereby causing said arm to eject said ball in a forward direction, said board having a transverse slot therethrough, said figure having spaced downward projections registering slidably in said slot, said figure thereby being slidable on said board in a transverse direction, said arm having a pivot pin on its upper extremity pivotally mounted on said figure, a

cross-arm secured to said pin, said resilient means comprising a spring having one end anchored to the figure and the other end anchored to one end of said cross-arm, said board having a passage through the end thereof extending into and at right angles to said slot, said first-named means comprising a flexible cord having one end anchored to the other end of said cross-arm and extending from said figure through said slot and said passage out of said board, the other end of said cord being adapted to be held in the hands and pulled.

HARVEY M. WESCOTT.
